US0D1031432S

(12) United States Design Patent (10) Patent No.: US D1,031,432 S
(45) Date of Patent: * Jun. 18, 2024

(54) PACKAGING BOX

(71) Applicant: Binggrae Co., Ltd., Namyangju-si (KR)

(72) Inventors: Hyejin Park, Seoul (KR); Eunji Kwon, Seoul (KR)

(73) Assignee: Binggrae Co., Ltd., Namyangju-si (KR)

() Term: 15 Years

(21) Appl. No.: 29/852,845

(22) Filed: Sep. 9, 2022

(30) Foreign Application Priority Data

Mar. 16, 2022 (KR) 30-2022-0010268

(57) CLAIM

The ornamental design for a packaging box, as shown and described.

DESCRIPTION

FIG. 1 is a perspective view of a packaging box according to the present invention; and,

FIG. 2 is a front view of the packaging box of FIG. 1. The broken lines depict structural environment and form no part of the claimed design. The dot-dash lines indicate the boundary of the claimed design and form no part of the claimed design.

1 Claim, 2 Drawing Sheets
